UNITED STATES PATENT OFFICE.

LORAN E. NEBERGALL, OF DENVER, COLORADO.

UNDERREAMER FOR HYDRAULIC ROTARY WELL DRILLING.

Application filed November 3, 1923. Serial No. 672,601.

To all whom it may concern:

Be it known that I, LORAN E. NEBERGALL, a citizen of the United States, residing in the city and county of Denver, State of 5 Colorado, have invented certain new and useful Improvements in Underreamers for Hydraulic Rotary Well Drilling, of which the following is a specification.

My invention relates to tools and appliances for drilling artesian and oil wells, and particularly to devices for use in connection with hydraulic rotary drilling mechanism. It is the object of my invention to provide a simple, durable, efficient and relatively inexpensive under-reaming tool, adapted for use in series with other hydraulic rotary drilling tools, and to operate beneath the lower end of the well-casing; for enlarging the hole formed by the usual bit or drill, whereby the casing may readily enter the enlarged portion of the hole. A further object of my invention is to provide a hydraulic rotary under-reamer with which the cuttings or material loosened thereby will be in a finely divided condition, so as to be freely carried out of the hole by the upward current of slush therein, and not "ball" or clog the slush-return passages. Further objects of my invention are to provide an under-reamer adapted to pass freely through the well-casing during the insertion and withdrawal of the string of drilling tools, to provide means by which the cutting blades of the reamer are automatically expanded by the hydraulic pressure from the slush-pumps when the drilling operations are started, and to provide means by which said blades are automatically forced inwardly to a retracted or folded position as the tool is raised from its operating position into the well-casing.

In the accompanying drawings Fig. 1 is a longitudinal or vertical section of an under-reamer embodying my invention, and showing portions of the devices associated therewith when it is in use, Fig. 2 is a side elevation of the same, and Figs. 3, 4 and 5 are detail horizontal or transverse sections, taken, respectively, on the lines 3-3, 4-4 and 5-5 of Fig. 1.

In carrying out my invention I provide a tubular stem 6 of which the longitudinal or axial opening 7 comprises the water-channel for conducting water or slush through the reamer to the bit or drill connected below the same. At each end of

said tubular stem there is a tapered threaded portion 8, similar to the pin-end of the usual tool-joints employed for connecting hydraulic drilling tools and stands of drill-pipe. Adjacent to the threaded end portions 8 are the cylindro-segmental neck-portions 9 and 10, having flat opposite sides as shown in Figs. 4 and 5. Adjacent to said neck-portions 9 and 10 the stem is shouldered outwardly to the diameter of the main body-portion, which is slightly conical or tapering from end to end, being smaller at the lower than at the upper end. In the outer part of the tapering body-portion, at opposite sides thereof, are longitudinal grooves or channels in which are disposed the folding wings or blades 11. The wing-grooves or channels are of uniform depth throughout their length, thus being divergent from their lower to their upper ends, or parallel respectively with diametrically opposite sides of the stem-body. The deepest portion of each groove is semi-cylindrical in sectional form, and the inner portions of the wings or blades fit pivotally therein so that they may swing in and out about longitudinal axes, from extended positions at which their outer edges project beyond the stem-body as shown in Fig. 3, to retracted or folded positions at which the blades lie wholly within the stem-body periphery as indicated by dotted lines in the same figure. Formed integrally with the upper and lower ends of the blades, adjacent to the neck-portions 9 and 10, are the pivot-pins 12 which fit rotatably in the pivot-plates 13 and 14. Said pivot-plates are of diameters the same as the respectively adjacent ends of the stem-body, and the thickness of said plates is the same as the length of the neck-portions, the central openings of the plates being of the same cylindro-segmental form as said neck-portions, whereby to fit slidably but non-rotatively thereon. The pivot-plates are retained in place upon the neck-portions of the stem by means of the caps or end-members 15 and 16, which are internally threaded to screw upon the pin-ends 8 of the stem. Each of said end-members or caps has a central passage or water-channel extending through the same and communicating with the channel 7 through the stem 6. At the ends adjoining the pivot-plates the caps are of the same diameter as the respective plates, and from said ends they are conically

tapered toward the opposite ends. In the illustrated structure the upper cap 15 is internally threaded at its upper end to receive the lower end of the drill-pipe 17, and the lower end of the lower cap 16 has an internal thread or box adapted to receive the pin 18 of a drill or other tool to be operated below the under-reamer.

In the operation of the under-reamer the same is rotated in the direction indicated in Fig. 3, and it will be seen that the wing-grooves are so shaped that when the blades are in extended position they will be supported at their rearward sides, while their inner semi-cylindrical edges are retained within the corresponding sockets or bottom-positions of the wing-grooves, whereby to effectively resist any tendency for the blades to be twisted out of the grooves or to cause excessive stresses upon the pivot-pins 12. In the retracted or folded positions of the blades, their flat front faces rest against the flat tangential faces 19 of the grooves in the stem. On the outer edges of the blades, at the upper portions thereof, are beveled or inclined portions 20, as shown, so that when the reamer is withdrawn or raised from its operating position and enters the lower end of the well-casing 21, the latter will engage said inclined edges 20 and cause the blades to swing to the folded positions within the grooves. A plurality of holes or passages 22 extend from the central water-channel 7 of the stem outwardly to the tangential faces 19 of the grooves. In the operation of the reamer, after the same has been lowered through the casing 21 with the blades in the folded position, a part of the water or slush, which is pumped down through the drill-pipe 17 to the water-channel 7 of the reamer-stem 6, is discharged through said passages 22, thus automatically causing the opening of the blades to the extended or operating position when the slush-pumps are started at the beginning of the drilling operation. The water or slush discharged through the passages 22 keeps the cuttings cleared from the blades during the operation, and the space kept open about the reamer-stem, by the cutting action of the blades, affords an ample passage for the upward or return flow of slush from the drill or bit operating below the reamer. By reason of the outward inclination or divergence of the blades, all portions of their rectilinear cutting edges are similarly utilized, and wear thereof is kept at a minimum. The reamer is so proportioned that at the lower end the blades will enter the hole formed by the drill or bit, while the reamed hole completed by the upper portions of the blades will be of such size that the well-casing 21 may freely enter the same, the enlargement of the drilled hole being from a diameter less than the inside

diameter of the casing to a diameter slightly greater than the outside diameter of the casing. It will be seen that as the reamer is gradually lowered, each portion of the long cutting edges of the blades will be required to remove only a very thin layer or shaving from the side of hole at each revolution, so that the material loosened by the reamer will be thoroughly disintegrated, and the shavings or scrapings detached by the blades will have no tendency to ball or clog, and will be readily carried up by the current of slush passing upward about the reamer from the drilling tools below, supplemented by the fluid emerging from the passages 22.

Now, having described my invention, what I claim and desire to secure by Letters Patent is:

1. A hydraulic rotary under-reamer, comprising a tapering tubular stem having longitudinal grooves in the outer portion thereof, said grooves being substantially parallel with the adjacent tapering surfaces of the stem, cutting blades mounted in said grooves and swingable inwardly and outwardly between folded positions wholly within said grooves and extended positions at which the longitudinal edges of the blades project laterally from the stem, said blades having inclined edges at the upper portions thereof adapted for engagement with the well-casing to swing the blades to their folded positions and the longitudinal cutting edges of the blades being parallel with the adjacent tapering surfaces of the stem, there being lateral passages extending from the central longitudinal passage of the tubular stem to discharge fluid therefrom into the longitudinal grooves, and means at the ends of said tubular stem for connecting the same with the other tools of a series.

2. A hydraulic rotary under-reamer, comprising a tubular stem having a tapered body-portion and provided with longitudinal grooves in the outer part thereof and lateral passages extending to said grooves from the central longitudinal passage, cutter blades disposed in said grooves and movable pivotally therein about longitudinal axes, whereby to extend laterally from the sides of the body or to fold into said grooves, pivot-pins at the ends of said blades, pivot-plates at the ends of said tapered stem-body for engaging said pivot-pins, means for securing said pivot-plates upon the stem-body, and tubular members at the ends of the stem-body for connecting the same with other tools of a series.

3. In a hydraulic rotary well drilling mechanism, an under-reamer comprising a tubular stem, means at the ends of said stem for connecting the same in series with other tools, the outer portion of said stem being longitudinally grooved and there being pas-

sages connecting said grooves with the central bore of the stem, and cutter blades disposed in said grooves and movable pivotally about axes extending longitudinally thereof, said blades having portions engageable by the well-casing to swing the blades into the grooves, the passages from the central bore of the stem being adapted to direct fluid therefrom against the blades in the

grooves, whereby to swing the same outwardly, the stem being tapered from the upper to the lower end thereof, and the pivotal axes and outer cutting edges of the blades being so inclined to the axis of the stem that the blades project uniformly beyond the tapering outer surface of the stem. 10 15

L. E. NEBERGALL.
